UNITED STATES PATENT OFFICE.

ALBERT R. PRITCHARD, OF ROCHESTER, NEW YORK, ASSIGNOR OF ONE-HALF TO CHARLES D. MILNE, OF SAME PLACE.

DESIGN FOR A BAIL-EAR FOR VESSELS.

SPECIFICATION forming part of Design No. 22,426, dated May 9, 1893.

Application filed April 5, 1893. Serial No. 469,211. Term of patent 14 years.

To all whom it may concern:

Be it known that I, ALBERT R. PRITCHARD, a citizen of the United States, and a resident of the city of Rochester, in the county of Monroe, State of New York, have invented and produced a new and useful Design for Bail-Ears for Vessels, of which the following is a specification, reference being had to the accompanying drawings, in which—

10 Figure 1, is a perspective view of the outer side thereof. Fig. 2, is an elevation thereof seen from the inner side. Fig. 3, is a bottom plan view thereof.

In the drawings A is the base which has a 15 trefoil form.

B is the upright portion integral with the base and is repoussé outwardly on a plane b substantially in circular form and has side- wise projecting portions b' b'.

CC are portions inwardly projecting in the 20 same plane and adjacent to the lower part of the circular portion b, and extending therefrom to join with the base A. The upright portion B and the base A are bent at an angle 25 to each other, as shown on the line x—x of Fig. 1. From the middle of the lower side of the circular portion b, a repoussé rib c extends between the portions CC, to the line x—x and thence along the medial line of the adjacent part of the base A, as shown. 30

What I claim is—

The design for a bail ear for vessels herein shown and described.

ALBERT R. PRITCHARD.
